UNITED STATES PATENT OFFICE.

ANTOINE BEDELMANN DU PONT, OF CLEVELAND, OHIO.

GAS COOKING STOVE AND RANGE.

1,282,056.

Specification of Letters Patent. Patented Oct. 22, 1918.

Application filed August 20, 1917. Serial No. 187,056.

To all whom it may concern:

Be it known that I, ANTOINE BEDELMANN DU PONT, citizen of the United States, residing at Cleveland, in the county of Cuyahoga and State of Ohio, have invented certain new and useful Improvements in Gas Cooking Stoves and Ranges, of which the following is a specification.

My invention relates to an improvement 10 in gas cooking stoves and ranges, and the improvement comprises the particular construction and arrangement of parts, all substantially as shown and described herein and more particularly pointed out in the claims. 15 The primary object of the invention is to promote perfect combustion at the burners beneath the top cooking plate of the range, but other objects are also embodied in the details of the structure as will hereinafter 20 appear.

In the accompanying drawings, Figure 1 is a plan view of a gas range embodying my invention and showing the oven and rear portion of the range in section to disclose 25 the exhaust flue at the rear of the cooking top of the range. Fig. 2 is a sectional view vertically and transversely of the range on line 2—2, Fig. 1. Fig. 3 is a sectional view vertically and longitudinally of the range, 30 looking toward the rear thereof, and showing the horizontal draft flue at the rear partly broken away where it opens into the vertical passage which communicates with the chimney flue back of the oven.

The invention as disclosed in these several views is predicated largely on the use of a horizontal draft passage or exhaust flue F for the products of combustion from the gas burners 2 within the chamber beneath the 35 top cooking plate of the range, and which draft flue communicates with the chimney flue 3 for the oven and its gas burners. In this connection it should be understood that the present range is of the type or style in 40 which the chamber or space 4 containing the gas burners 2 is designed to be closed over its top during use. Thus, the holes in the top plate over the burners have lids to prevent the escape of gas fumes from 45 the range, and if these lids are removed in cooking operations the holes will be closed generally by the pans or vessels set thereon. It follows therefore that in a range of this kind where the products of combustion are 50 not intended to be discharged into the room a suitable draft channel must be provided to 55 carry them off or imperfect combustion will occur. Perfect combustion also presupposes an adequate supply of fresh air to the burners, and while this is easily obtained if 60 the draft passages are sufficiently large and open, I have found that it is also essential to properly locate the exhaust flue F relatively to the burners to obtain the most efficient working results. The invention 65 herein therefore begins at this point and is differentiated from all other ranges of this general type or style known to me by the simple flue construction directly associated with the burners 2 and the chambered space 70 4 in which they are located and which is clearly outlined in the drawings. As to this space the top plate 5 of the range constitutes the top of the chamber, and the pan 6 may be regarded as the bottom thereof, although 75 said pan is usually a removable part of the range. The rear wall of the range forms the back of the chamber as a matter of fact, but an angle plate 7 which is secured to said wall and extends horizontally the full width 80 thereof, may also be considered the back wall of said chamber. This plate 7 forms a horizontal exhaust flue F of ample size to accommodate the needs of all the burners in chamber 4, but in order that the burnt 85 products and used air be carried away promptly from the burners and to stimulate the flow of fresh air to the burners, the entrance or opening 8 to the exhaust flue F is especially placed lengthwise at the 90 top of said flue in close proximity to top plate 5. The flue may be of the relative size shown in the drawings providing it has a capacity in depth and width commensurate to the needs of all the burners, and as shown 95 the said flue extends below the plane of the burners while also extending above the same, and the slot or opening 8 is on a higher horizontal plane than the top of the burners. The elevated position of the slot relatively to the burners is important in that a 100 positive and constant updraft is thereby produced in chamber 4 to supply the burners with fresh air and at the same time clear the space beneath the top plate from the burnt products of combustion. The present construction is also exceptional and original in that the horizontal flue F is built of a single angular strip of sheet metal secured upon the inside of the rear wall and occupies 110 a space otherwise of no utility in the range but of ample capacity for my purpose, and

by merely separating the upper edge of the strip from the top plate 5 I produce an elongated opening and entrance 8 to the flue above the top plane of the burners 2. The 5 outlet for this horizontal flue is at the end thereof at opening 10 in division wall 11 of the range, and, which wall separates the cooking side of the range from the baking and broiling oven 12. This oven rises to 10 a higher elevation than top plate 5 and has a vertical draft space or passage 14 at the rear thereof in line with exhaust flue F (see Fig. 1), and the chimney flue 3 is connected with the upper end of this passage 15 and serves to carry away the products of combustion from the burners 2 in chamber 4 and also the burner 15 within the oven 12. Moreover, by arranging and building 20 the flues as described I am enabled to construct the range with a smooth plain back wall without protruding parts and the construction thereof is greatly simplified and the cost reduced, especially as no castings, elbows or special joints are required to unite 25 the flue sections.

What I claim is:

1. A cooking range having a top cooking plate and a burner chamber and gas burners beneath said plate and provided with an 30 oven at one side of said plate having a verti-

cal draft passage at its rear and a chimney flue open to said passage, and said burner chamber having a horizontal exhaust flue at its rear open at one end of said vertical draft passage and arranged opposite the gas 35 burners therein and also open in its upper portion for the exit of products of combustion from the top of said chamber above the top plane of said burners.

2. A kitchen range having separate cooking and baking chambers with a continuous plain wall at the rear of said chambers and draft flues on both chambers within said wall and a chimney flue open to both said draft flues, the draft flues to the cooking 45 chamber comprising a sheet metal strip bent to form said flues and having a continuous opening longitudinally along its top to receive the products of combustion from burners in said chamber, and the said baking chamber having an inside draft flue open to said cooking draft flue and to said chimney flue, a top plate over said cooking chamber and burners therein on a plane below the opening to the draft flue at the rear 50 thereof.

Signed at Cleveland, in the county of Cuyahoga and State of Ohio, this 4th day of May, 1917.

ANTOINE BEDELMANN DU PONT.
